UNITED STATES PATENT OFFICE.

CATHERINE C. B. ALFREDS, OF CHICAGO, ILLINOIS.

CORSET.

1,096,089.

Specification of Letters Patent.

Patented May 12, 1914.

Application filed June 14, 1913. Serial No. 773,605.

To all whom it may concern:

Be it known that I, CATHERINE C. B. ALFREDS, a citizen of the United States, and a resident of Chicago, in the county of Cook 5 and State of Illinois, have invented certain new and useful Improvements in Corsets; and I do hereby declare that the following is a full, clear, and exact description thereof, reference being had to the accompanying 10 drawings, and to the letters of reference marked thereon, which form a part of this specification.

This invention relates to improvements in corsets and consists of the matters herein- 15 after described and more particularly pointed out in the appended claim.

The invention relates more particularly to that type of corset known as the "long hip" or long waist corset wherein the corset is 20 provided with a skirt which extends below the corset stays to confine the fleshy portion of the hips and produce a narrow, straight hip effect. When such a corset as now constructed is worn, the wearer finds it very in- 25 convenient, when performing the natural excretory functions, on account of the bound condition of the muscles and organs of the body covered by the skirt.

The object of my invention is to produce a 30 long hip corset which is free of the objection mentioned, while at the same time, retaining for the wearer, the desired straight hip figure effect under the usual conditions of standing and sitting.

35 The advantages of my improved corset will appear as I proceed with my specification.

In the drawings:—Figure 1 is a three quarter perspective view of a front lace cor- 40 set made in accordance with my invention illustrating the parts of the corset in position when the wearer is in a standing position. Fig. 2 is a view similar to Fig. 1 illustrating the position of the parts of the 45 corset as they are arranged when performing the natural excretory functions. Fig. 3 is a fragmentary view in rear elevation illustrating the manner in which the invention is applied to a long hip corset of the back lac- 50 ing type.

Referring now to that embodiment of my invention illustrated in the accompanying drawings, 5 indicates the body of a front lacing corset. The said body is provided 55 with the usual stays 6 which extend from the top of the corset downward to a line of

stitching 7. The flexible material forming the body of the corset is extended below the line of stitching 7 to form a skirt 8 which comes to or below the hips of the wearer and 60 may extend below the end of the spine.

The function of the skirt member 8 is to confine the hips and the fleshy parts of the body thereabout to produce a neat molded straight line figure effect and is constructed 65 to fit the hips snugly.

In my improved corset of this type, I have provided in the skirt member a flap member 9 made from the same material as the body of the corset. The said flap member 9 is located at the back of the corset and is of a depth equal the depth of the skirt 8. In width I find it preferable to extend it around at each side to where the rear hose supports 11 are attached to the skirt 8. The said flap has lateral marginal extensions 10 provided with eyelet members 10^a, 10^a, which contact with shank members 12 of suitable snap fastening devices attached to the marginal parts of the skirt 8. This construction forms 80 no projection in the wearer's clothing noticeable from the outside and is so positioned as to be readily accessible for fastening or unfastening the snap fasteners.

The flap 9 when in the position illustrated 85 in Fig. 1, wherein the wearer is shown as in a standing position, will stand the strain of the movement of the muscles under all conditions and act as a part of the skirt 8. When seated, and after lifting her skirts, 90 the wearer may easily detach the flap 9 and raise it upwardly to the position shown in Fig. 2, when the rest of the skirt 8 is free to accommodate the muscles which will then assume their normal natural position. When 95 the wearer is again in a standing position, the flap 9 is let down and attached to the skirt 8 and then becomes a part of said skirt.

In Fig. 3 I have illustrated my invention 100 as applied to what is known as a back-lacing corset. In this instance 15 indicates the body of the corset which comprises two half body sections 15^a, 15^a, joined together at the rear by means of a lacing 16, which extends 105 from the top edge to the bottom edge of the corset. 19 indicates the skirt members, one made integral with each half section 15^a, and 20, 20 indicate flap members secured to each half section 15^a at the line of stitching 18. 110 The lacing 16 extends down below the corset body proper and connects with the flap mem-

bers 20, 20. The lateral marginal parts of the flaps 20, 20 overlap the margins of the skirt and coacting snap fastening devices 21, 22 are provided as before for detachably securing the flap members to the skirt members.

I claim as my invention:—

A corset having a main stiffened body part and an unstiffened skirt part projecting below said body part, said unstiffened skirt part including a flap at the back adapted to be

swung upwardly, and means for detachably attaching the lateral edges of said flap to said skirt part.

In testimony, that I claim the foregoing as my invention I affix my signature in the presence of two witnesses, this 11th day of June A. D. 1913.

CATHERINE C. B. ALFREDS.
